UNITED STATES PATENT OFFICE.

JOSEPH ANTLEY FAIRCHILD, OF FOREST, MISSISSIPPI, ASSIGNOR TO VIOLA VIRGINIA ANTLEY, OF FOREST, MISSISSIPPI.

OVEN.

1,143,372.

Specification of Letters Patent. Patented June 15, 1915.

Application filed July 3, 1914. Serial No. 848,772.

To all whom it may concern:

Be it known that I, JOSEPH A. FAIRCHILD, a citizen of the United States, residing at Forest, in the county of Scott and State of Mississippi, have invented a new and useful Improvement in Ovens, of which the following is a specification.

This invention relates to stove ovens, and one of the principal objects of the invention 10 is to provide an oven having a number of sliding drawers for receiving the baking receptacles, the drawers being so constructed as to allow the circulation of heat throughout the oven, and being adapted to be individually withdrawn without disturbing the remainder whereby to allow access to the contents of any particular drawer with the loss of a minimum amount of heat from the oven.

20 Another object of the invention is to provide an oven of the class described which will be extremely simple, durable, efficient in operation and inexpensive to manufacture.

25 With these and other objects in view which will become apparent as the description proceeds, the invention resides in the construction, combination and arrangement of parts, hereinafter more fully described 30 and claimed, and illustrated in the accompanying drawing, in which like characters of reference indicate like parts throughout the several figures, of which:

Figure 1 represents a front elevational 35 view of an oven constructed according to my invention, portions being broken away to disclose the interior of the oven. Fig. 2 represents an enlarged vertical longitudinal sectional view taken on the plane indicated 40 by the line 2—2 of Fig. 1, and Fig. 3 represents a perspective view of one of the drawers, portions being broken away.

Referring more particularly to the drawing, the oven is open at its front, and includes a top and bottom 5 and 6 respectively, sides 7 and a back 8. Although the oven is of a construction ordinarily utilized in oil stove ovens, it is to be understood that my invention is applicable to ovens in gas stoves, 50 ranges, etc. Arranged on the inside of the oven and secured to the side walls 7, are pairs of guides in the form of channel irons 9, disposed one above the other. Said irons are adapted to guide the drawers as

the latter are inserted or withdrawn from 55 the oven.

Each drawer comprises a frame work including side bars 10, end cross bars 11, and transverse bars 12. The frames form the bottoms of the drawers and while serving 60 to support the baking utensils allow of a free and uniform circulation of heat throughout the oven, so that the heat in the portion of the oven occupied by one drawer will be equal to that occupied by the others. 65

The end bars 11 are extended laterally of side bars 10 as at 13. These extensions 13 form engaging lugs adapted to slide in the channel irons 9, whereby the drawers may be inserted and supported within the oven, 70 and guided in their movement as will be readily understood. Each drawer is provided with a rear wall 14 in the form of a plate, and a front wall 15. This may be flat or may be of the form illustrated in the 75 drawing. The sides of the drawer are open, and to the front plate is secured a knob 16 by means of which the drawer may be manipulated.

The front and rear walls are supported 80 by means of uprights 16 occurring at each corner of the frame work, and forming extensions of the side bars 10. The uprights or standards are braced by means of the inclined bars or extensions 17, which may be 85 integral with the uprights as shown and connected in any suitable manner with the side bars 10. The frame together with the corner braces may be formed in any suitable and desirable manner. 90

In the embodiment shown end bars 11 are soldered or otherwise suitably fastened to the frame at the junction points of bars 10 with the uprights 16. The rear walls 14 are of a width equal to the width of the frame 95 and of a height equal to the height of the adjacent uprights 16. The front walls are slightly longer than the width of the frame, so that when in position the ends 18 of the front walls will engage against or abut the 100 front edges of side wall 7 of the oven, to provide a snug fit. The width or height of the front walls is such that when the drawers are in position the upper and lower edges of the topmost and lowermost walls 105 respectively will snugly fit against the edges of top 5 and bottom 6 respectively, of the oven. The adjacent edges of the front walls

will also snugly fit against each other, so that a closure will be formed which will prevent escape of heat from the oven, except when the drawers are withdrawn.

5 By the structure set forth it will be evident that any individual drawer may be withdrawn without disturbing the remaining ones, and that instead of the entire closure of the oven being thrown open as is the 10 case in the ordinary structure, only that portion of the closure occupied by the front wall of the drawer will be open. Thus only a minimum amount of heat will escape and in this manner as near a uniform temperature as possible will be maintained within the oven. This arrangement also eliminates to a great extent the very objectionable feature accruing to the ovens of ordinary construction, which resides in the fact that upon 15 the opening of the oven door a great volume of heat is thrown directly into the face of the person. It will be understood of course that with my oven the amount of heat liable to escape will be minimized and for this 20 reason this objection will be overcome to a great extent.

Although I have described the preferred

embodiment of my invention, I may desire to make such changes in the construction, combination and arrangement of parts thereof as do not depart from the spirit of the invention and the scope of the appended claim.

I claim:—

The combination with an oven having an 35 open front, of a plurality of drawers slidably disposed therein and being each formed of an open framework whereby to provide for uninterrupted circulation of heat throughout the oven, and a plurality of 40 front walls provided one for each drawer and adapted when the drawers are in closed position to form of themselves a closure for the oven, the ends of the front walls overhanging and abutting against the edges of 45 the oven at its ends, and the upper edge of the topmost front wall and the lower edge of the lowermost front wall overhanging and engaging against the edges of the oven at the top and bottom of the latter.

JOSEPH ANTLEY FAIRCHILD.
